TRANSFORMER TANK BRACING

Karl P. Wiederkehr, Elm Grove, Wis., assignor to Allis-Chalmers Manufacturing Company, Milwaukee, Wis.

Filed July 5, 1957, Ser. No. 670,313

8 Claims. (Cl. 336—92)

This invention relates in general to transformer tanks. More specifically this invention relates to an improved bracing for a transformer tank.

Transformer tanks must withstand a variety of internal and external pressures. During assembly the tank is placed under vacuum for oil filling and later the oil is pressurized to test the tank for leaks. The oil is drained for shipping and the transformer is refilled under vacuum in the field. Although some transformers operate at atmospheric pressure, others are sealed and the pressure in the tank varies as the volume of the oil in the tank changes with heating and cooling.

When the changes in the oil volume would cause excessive pressure variations in a closed system, a relief device in combination with a supply of compressed gas is provided to limit the pressure variation.

The walls of a transformer tank are often braced by ribs to withstand the pressure variations. On the long flat sides of a three phase transformer, the bracing required to provide the tank with the rigidity to withstand the pressure variations may be very heavy. If wall to wall bracing were used inside the tank, the overall bracing required could be reduced. However, it is usually very difficult and impractical to assemble wall to wall bracing inside the tank.

In one method of transformer construction, the coil assemblies are mounted on a common horizontal axis and a yoke surrounds the coil assembly in a vertical plane. When the core and coil assembly has been completed it is lowered into the tank. A pair of notched plates at each end of the core cooperate with vertical rails inside the tank to guide the core and coil assembly into the tank and to position it. However, the coil assembly is nearly in contact with the sides of the tank, and central locations for internal bracing are inaccessible after the coil and core assembly has been placed in the tank. In some transformers of this construction braces are positioned between the walls of the transformer tank above the core. However, this support is inefficient because the braces are not centrally located with respect to the tank wall and interfere with the electrical connections at the top of the transformer.

In this invention plates are attached to core clamps positioned between the coils of the transformer and flanged bars are mounted on the tank wall for receiving the plates. The plates interlock with the flanges on the bars when the coil assembly is placed inside the tank. The plates and the bars cooperate to brace the tank walls against internal pressure and the outer faces of the plates brace the walls against external pressure. Since it is only necessary to restrict the wall movement to within the elastic limits of the wall material, the transformer wall bracing of this invention can be made and installed within the usual manufacturing tolerances.

Therefore it is an object of this invention to provide a new and improved bracing for the walls of a transformer tank.

Other objects and advantages will be apparent from the

2

following description when read in connection with the following drawings in which:

Fig. 1 is a plan view of a three phase transformer with the top cover of the transformer tank removed;

Fig. 2 is a section taken along line II—II of Fig. 1; and

Fig. 3 is an enlarged view of the interlocking plate and bar of the tank bracing.

The transformer tank bracing of this invention is shown in Fig. 1 in connection with a three phase transformer

10 having three axially spaced cylindrical coil assemblies 11 which are mounted in the windows 12 of a rectangular core 13. The core 13 is clamped at either end between pairs of oppositely facing end frames 16 which are connected by bolts 17 passing under and over the core 13.

15 Similar pairs of frames 18 clamp the core 13 intermediate the coil assemblies 11 by means of connecting bolts 17. The coil assemblies 11 are clamped between oppositely facing clamping plates 21 and 21a. The coil clamping plates 21 and 21a may be mounted on the transformer

20 in any suitable way but preferably as shown, the plates 21 clamping the two outer coil assemblies are attached to the end frames 16 and the intermediate frames 18. The center coil assembly is clamped between floating clamping plates 21a which are pressed against center coil assembly

25 by means of jacking bolts 22 (only one of which is shown) acting against the fixed clamping plate 21 of the adjacent outer coil assembly. The core and coil assemblies are positioned within the transformer tank 23.

The transformer tank wall brace 25 of this invention 30 comprises an arm 26 extending from the intermediate frames 18 toward the wall 27 of the transformer tank 23, a plate 28 attached to the outer end of the arm, and a flanged bar 29 attached to the tank wall. Preferably a plurality of such braces are used with each transformer.

35 The arm 26 is attached at its inner end to an intermediate frame 18 and may be supported along one side by the fixed coil clamping plate 21. Any suitable supporting structure may be used for the arm but an angle iron is illustrated. The arms 26 are located on the frames

40 18 to position the plates near the horizontal center line 30 of the tank 23. Since the transformer tank 23 extends above the core and the coils, the arms are positioned above the center line of the coils. This position is desirable also because the arm is clear of the jacking bolts 22 which are located toward the center line of the coils.

45 The flat side of the plate 28 attached to the arm 26 is substantially parallel with the tank wall 27. An edge or portion 32 of the plate preferably extends below the arm for engaging the bar 29. If desired, additional support for the plate 28 may be provided such as the support 33 positioned between the arm and the upper part of the plate.

50 The flanged bar 29 is mounted on the tank wall 27 in any suitable way such as by welding. The flanged portion 35 of the bar 29 is removed from the tank wall 27 and extends in an upward direction. The flanged portion cooperates with the wall 27 to form a groove 36 for receiving the portion 32 of the plate 28 that extends below the arm 26.

55 In assembly it is preferable to mount the arm 25 and the plate 28 on the clamping frames 18 before clamping the frames on the core. However, the arm and plate may be assembled at any time before the coil and cores are placed in the tank. The flanged bar 29 is mounted on the tank wall 27 during the assembly of the transformer tank. When the coil and core assembly is lowered into the tank, the lower portion 32 of the plate 28 enters the channel 36 formed by the flange of the bar and the tank wall. The plates 28 are held rigid by arms 60 which are connected by the intermediate frames, the frame connecting bolts and the intervening core material.

In operation the upward projecting flange 35 of the bar 29 and the downward projecting portion 32 of the plate 28 cooperate to limit the outward movement of the tank walls caused by internal pressure. When the tank is under vacuum, the plates 28 abut the tank walls to limit the inward movement of the walls.

Although but one embodiment of his invention has been illustrated, it will be apparent to those skilled in the art that variations are possible within the scope of the appended claims.

What is claimed is:

1. A wall brace for transformer tanks comprising an arm mounted on the core frame of the transformer, a plate mounted on the free end of said arm, said plate being positionable adjacent a wall of the transformer tank, and a bar mounted on said wall, said bar having a flange removed from said wall to form a groove for receiving said plate.

2. A wall brace for transformer tanks comprising an arm mounted on the core frame of the transformer, a plate mounted on the free end of said arm, the flat side of said plate being positionable adjacent a wall of the transformer tank and the edge of said plate extending below said arm, and a bar mounted on said wall, said bar having a flange removed from said wall to form a groove for receiving said edge of said plate.

3. A wall brace for transformer tanks comprising an arm mounted on the core frame of the transformer, a plate mounted on the free end of said arm, said plate being positionable adjacent a wall of the transformer tank and having a portion extending below said arm, and a bar mounted on said wall, said bar having a flange removed from said wall to form a groove for receiving said plate.

4. A wall brace for transformer tanks comprising an arm mounted on the core frame of the transformer, a plate mounted on the free end of said arm, said plate being substantially parallel to a wall of the transformer tank and having a portion extending below said arm, and a bar mounted on said wall, said bar having a flange removed from said wall to form a groove for receiving said plate portion below said arm.

5. A wall brace for transformer tanks comprising an arm mounted on the core frame of the transformer and extending outward toward a wall of the tank, a plate mounted on the free end of said arm and positionable near the horizontal center line, said plate being substantially parallel to said wall and having a portion extending below said arm, and a bar mounted on said wall, said bar having a flange removed from said wall to form a groove for receiving said plate extension.

10 6. A wall brace for transformer tanks comprising arms mounted on the core frames of the transformer, a plate mounted on the free end of each of said arms, said plates being substantially parallel to the walls of the transformer tank, and bars mounted on said walls and positionable adjacent said plates, said bars having a flange removed from said walls to form grooves for receiving said plates.

7. A transformer comprising a core and coil assemblies spaced along said core, said transformer being positioned within a tank, core frames positioned intermediate said coil assemblies for clamping said core, arms mounted on said frames and extending outwardly toward the walls of said tank, plates mounted on the free end of said arms, and bars mounted on said walls and positioned adjacent said plates, said bars having a flanged portion spaced from said walls to define grooves for receiving said plates.

8. A transformer comprising a core and coil assemblies spaced along said core, said transformer being positioned within a tank, core frames positioned intermediate said coil assemblies for clamping said core, arms mounted on said frames and extending outwardly toward the walls of said tank, plates mounted on the free end of said arms, said plates being substantially parallel to said walls and positioned near the horizontal center line of said tank, and bars mounted on said walls and positioned adjacent said plates, said bars having a flanged portion spaced from said walls to define grooves for receiving said plates.
